AUTOMATIC TELEGRAPH TRANSMITTER

Laurance E. Gardiner, Stratford, N. J.; Arthur N. Gardiner, administrator of said Laurance E. Gardiner, deceased, assignor to Arthur N. Gardiner, individually

Application September 5, 1945, Serial No. 614,487

10 Claims. (Cl. 200—46)

1

This invention relates to automatic telegraph transmitters, and more particularly to devices for automatically controlling electrical circuits for the transmission of messages. The device is also particularly useful in the teaching of code to beginners, as it enables them to learn quickly to recognize the code signals used in telegraph work.

The invention relates to that type of instrument in which a perforated tape is fed through the same, and in which, as the perforations in the tape pass a metallic brush, contacts are made and broken, and in this manner the sending of a telegraph message is effected or simulated.

More specifically considered the present invention relates to certain improvements on that type of instrument which is shown and described in my previous Letters Patent, No. 2,285,268, granted June 2, 1942.

In the device shown in my aforesaid Letters Patent No. 2,285,268, the tape spools, and part of the driving mechanism for the same, were on the outside of the cabinet or housing, but in the present device practically everything is enclosed, with the exception of a small portion of the perforated tape, including the part which is being used in the making and breaking of the circuit, this portion being fed over a bulge on the front of the cabinet where it is exposed to the view of the operator.

It has been found in practice that one of the principal difficulties in connection with the use of instruments of this character arises out of the circumstance that they get into the hands of that type of persons who like to tinker with any machine which they are using, and as certain of the internal parts are more or less delicate, short circuits causing considerable damage to the instrument are likely to occur.

The principal object of the present invention is to provide an instrument of the character aforesaid, which is so constructed and arranged that the parts will be effectively protected against injury including that caused by unskillful tinkering with the internal parts of the device.

A further object of the invention is to provide, in an instrument of the character aforesaid, means for opening the circuit automatically to prevent the use of the instrument whenever the lid is raised for the purpose of access to the tape spools for the purpose of changing the tape thereon.

The nature and characteristic features of the invention will be more readily understood from the following description, taken in connection

2

with the accompanying drawings forming part hereof, in which:

Figure 1 is a perspective view, showing more particularly the external appearance of apparatus embodying the main features of the present invention;

Fig. 2 is a top or plan view of the lower portion of the device with the lid removed, and with certain other portions removed, and with parts shown in section;

Fig. 3 is a fragmentary plan view of a portion of the mechanism shown in Fig. 2, but with the parts in positions assumed when the lid of the cabinet is raised;

Fig. 4 is a transverse vertical section of the upper portion of the cabinet, with the lid in the closed position and with certain of the parts in their operative positions, but with certain of the other parts omitted; and

Fig. 5 is a perspective view of a portion of the cabinet, particularly illustrating a guard or cover for a portion of the apparatus of the present invention.

It should, of course, be understood that the description and drawings are illustrative merely, and that various changes and modifications may be made in the structure disclosed without departing from the spirit of the invention.

Referring to the drawings, in the particular embodiment of the invention therein shown, 10 is a box or cabinet, in the interior of which the operating mechanism of the instrument is contained. To the main or body portion of the cabinet 10, a lid 11 is mounted by means of a hinge 12. The body portion of the cabinet 10 is preferably provided with a horizontal partition 13 below which the operating mechanism, not shown, of the instrument is disposed, and above which spools 14 and 15 are mounted on vertical spindles 16 and 17 respectively.

The driving wheel 18 of the operating mechanism, is arranged on the upper end of a vertical shaft 19, which is driven by a suitable motor, not shown, forming part of the operating mechanism which is disposed below the horizontal partition 13. The drive wheel 18 engages the periphery of an idler wheel 20 which is mounted on a vertical spindle 21 supported by the horizontal partition 13 of the cabinet. The idler wheel 20 is preferably provided with a resilient rim 22 made of rubber or the like.

The spindle 16 upon which the spool 14 is mounted is fixedly positioned in the horizontal partition 13, whereas the spindle 17 upon which the spool 15 is mounted is carried by one end of

a swinging arm 23 suitably tensioned by means of a spring, not shown, to cause the tape 24, which is wound on the spool 15, to bear at its peripheral portion against the resilient rim 22 of the idler wheel 20. The foregoing arrangement is provided so that the tape 24 will be moved at uniform speed during the operation of the instrument, notwithstanding the increase in diameter of the coil of tape on the spool 15 as the instrument continues to operate.

The body portion of the housing or cabinet 10 is provided with a lug 25, the outer surface of which is curved to provide a support, over which the tape 24 is fed, at a location where the same is visible to the operator.

The lid portion of the cabinet is provided with a lug or projection 26, complementary to the lug 25 of the body portion of the cabinet 10, and this lug 26 is also provided with a downwardly extending lip 27 which serves to shield a metallic contact member 28. The contact member 28 is mounted on the under face of the lug 26 of the lid portion 11 of the cabinet, and is adapted to be positioned in front of a portion of the tape 24 as the same is fed over the curved surface of the lug 25 of the body portion of the cabinet 10.

The lug 25, and the adjacent portion of the body of the cabinet 10, is provided with a recess 29 in which a metallic brush 30 is mounted. The brush 30 is secured in any suitable manner in the recess 29, as for instance by means of the screw 31. The free end of the brush member 30 is adapted, when the tape is fed over the curved surface of the lug 25, to extend through the perforations in the tape, and thereby to make contact with the metallic member 28 to close the circuit.

In the operative condition of the apparatus the brush member is impelled forwardly, to cause the free end thereof to make the contacts, as before stated, by means of a spring 32 which is also mounted in the recess 29, and is secured in place by means of screws 33. The free end of the spring 32, where the same engages the brush 30, is provided with an insulating sleeve 34 which serves to prevent the current from passing directly from the spring 32 to the brush 30.

When the lid 11 is raised the parts will be in the positions shown in Fig. 3 of the drawings, and the free end of the brush 30 will be retracted so that no contact can be made at this point, but in the normal operating condition a pin 35, which is mounted in the lug portion 26 of the lid will engage the spring 32 and impel the same forwardly, to cause the free end of the brush 30 to make the contacts through the perforations of the tape 24, as the same is fed over the curved surface of the lug 25. It should be noted that the pin 35 is tapered and at all times contacts with the metallic member 28 so that, when the circuit is established at the end of the brush 30, the current will pass through the metallic member 28 and thence through the pin 35 to the spring 32. The brush member 30 and the spring member 32 are respectively connected, by wires 50 and 51, to the main signaling circuit of the instrument to control the same. In the actual construction these wires are preferably concealed from view. The cabinet 10 may, if desired, be provided on its front face with binding posts 36 and 37 for connection of the instrument to the sounder, and also, if desired, the operating spindles 38 and 39 of the main switches of the instrument may extend from the front of the cabinet, the spindle 38 being provided for the control of the signaling

circuit and the spindle 39 being provided for the control of the motor circuit.

It has not been deemed necessary to illustrate the motor and other operating parts of the instrument, as the same may be varied according to the desire of the designer, and an operable arrangement thereof is shown in my previous Letters Patent hereinbefore referred to.

The brush 30 and spring member 32 contained within the recess 29 are protected by means of a cover plate 40, the horizontally disposed portion 41 of which extends over the top of said recess 29, and has a vertically depending portion 42 which extends downwardly on the inside. The horizontally extending portion 41 of the said cover plate 40 is provided with an aperture 43 through which the tapered pin 35 may pass when the lid is closed.

It will be seen that by the foregoing arrangement there is provided a simple and efficient device which will serve to open automatically the signaling circuit, whenever the lid of the cabinet is opened for the purpose of affording access to the spools upon which the perforated tape is mounted. In the use of the apparatus the purchaser will be warned that the removal of the cover plate 40 will result in loss of guarantee as to the performance of the apparatus, hence in the normal use of the device the signaling circuit will always be open whenever the lid is raised.

I claim:

1. In an automatic telegraph transmitter of the character described having contacts controlled by a movable perforated tape, the combination of a housing adapted to enclose the operating parts, said housing having a movable lid portion, contact making members including a brush member adapted to have its free end pass through the perforation of the tape to make contact with another of the contact-making members, said brush member being in inoperative position when the lid is open, and a member carried by the lid impelling said brush member to operative position when the lid is closed.

2. In an automatic telegraph transmitter of the character described having contacts controlled by a movable perforated tape, the combination of a housing adapted to enclose the operating parts, said housing having a movable lid portion, a contact member having a portion positioned adjacent the tape when the lid is closed, a brush member adapted to have its free end pass through the perforations in the tape to contact the aforesaid contact member, said brush member being in inoperative position when the lid is open, and a member carried by the lid for impelling said brush member to operative position when the lid is closed.

3. In an automatic telegraph transmitter of the character described having contacts controlled by a movable perforated tape, the combination of a housing adapted to enclose the operating parts and having a protruding portion at the front over which the tape visibly passes, said housing also having a movable lid portion, a contact member having a portion positioned adjacent the tape when the lid is closed, a brush member adapted to have its free end pass through the perforations in the tape to contact the aforesaid contact member, and means for retracting the brush member when the lid is opened.

4. In an automatic telegraph transmitter of the character described having contacts controlled by a movable perforated tape, the combination of a housing adapted to enclose the

operating parts, said housing having a movable lid portion, a contact member having a portion positioned adjacent the tape when the lid is closed, a brush member adapted to have its free end pass through the perforations in the tape to contact the aforesaid contact member, a spring having a portion bearing against the brush member, and means adapted when the lid is closed to stress said spring and cause the same to impel the free end of the brush to operative position.

5. In an automatic telegraph transmitter of the character described having contacts controlled by a movable perforated tape, the combination of a housing adapted to enclose the operating parts, said housing having a movable lid portion, a contact member having a portion positioned adjacent the tape when the lid is closed, a brush member adapted to have its free end pass through the perforations in the tape to contact the aforesaid contact member, a spring having a portion bearing against the brush member, and means adapted when the lid is closed to stress said spring and cause the same to impel the free end of the brush to operative position.

6. In an automatic telegraph transmitter of the character described having contacts controlled by a movable perforated tape, the combination of a housing adapted to enclose the operating parts and having a protruding portion at the front over which the tape visibly passes, said housing having a movable lid portion, a contact member carried by said lid and having a portion positioned adjacent the tape when the lid is closed, a brush member adapted to have its free end pass through the perforations in the tape to contact the aforesaid contact member, a spring having a portion bearing against the brush member, and means adapted when the lid is closed to stress said spring and cause the same to impel the free end of the brush to operative position.

7. In an automatic telegraph transmitter of the character described having contacts controlled by a movable perforated tape, the combination of a housing adapted to enclose the operating parts and having a protruding portion at the front over which the tape visibly passes, said housing having a movable lid portion, a contact member carried by said lid and having a portion positioned adjacent the tape when the lid is closed, a brush member adapted to have its free end pass through the perforations in the tape to contact the aforesaid contact member, a spring having an insulated portion bearing against the brush member, and a member carried by the lid and adapted when the lid is closed to stress said spring and cause the same to impel the free end of the brush to operative position.

8. In an automatic telegraph transmitter of the character described having contacts controlled by a movable perforated tape, the combination of a housing adapted to enclose the op-

erating parts and having a protruding portion at the front over which the tape visibly passes, said housing having a movable lid portion, a contact member carried by said lid and having a portion positioned adjacent the tape when the lid is closed, a brush member adapted to have its free end pass through the perforations in the tape to contact the aforesaid contact member, a spring having an insulated portion bearing against the brush member, and a tapered pin carried by the lid and adapted when the lid is closed to bear against said spring and cause the same to be stressed to impel the free end of the brush to operative position.

15 9. In an automatic telegraph transmitter of the character described having contacts controlled by a movable perforated tape, the combination of a housing adapted to enclose the operating parts and having a protruding portion at the front over which the tape visibly passes, said housing having a movable lid portion, a contact member carried by said lid and having a portion positioned adjacent the tape when the lid is closed, a brush member adapted to have its free end pass through the perforations in the tape to contact the aforesaid contact member, a spring having an insulated portion bearing against the brush member, a tapered pin carried by the lid and adapted when the lid is closed to bear against said spring and cause the same to be stressed to impel the free end of the brush to operative position, and a cover plate adapted to enclose certain of said contact members.

20 10. In an automatic telegraph transmitter of the character described having contacts controlled by a movable perforated tape, the combination of a housing adapted to enclose the operating parts and having a protruding portion at the front over which the tape visibly passes, said housing having a movable lid portion, a contact member carried by said lid and having a portion positioned adjacent the tape when the lid is closed, a brush member adapted to have its free end pass through the perforations in the tape to contact the aforesaid contact member, a spring having an insulated portion bearing against the brush member, a tapered pin carried by the lid and adapted when the lid is closed to bear against the said spring and cause the same to be stressed to impel the free end of the brush to operative position, and a cover plate adapted to enclose certain of said contact members, said cover plate having an aperture for the passage therethrough of the spring engaging pin.
